UNITED STATES PATENT OFFICE.

MIRABEAU N. LYNN, OF RISING SUN, INDIANA, ASSIGNOR TO THE LYNN ENGINE COMPANY, OF DAYTON, OHIO.

STEAM-BOILER.

SPECIFICATION forming part of Letters Patent No. 377,460, dated February 7, 1888.

Application filed December 28, 1886. Serial No. 232,808. (No model.)

To all whom it may concern:

Be it known that I, MIRABEAU N. LYNN, of Rising Sun, in the county of Ohio and State of Indiana, have invented certain new and useful 5 Improvements in Boilers; and I do hereby declare the following to be a full, clear, and exact description of the same, reference being had to the accompanying drawings, forming part of this specification, and to the figures 10 and letters of reference marked thereon.

This invention relates to improvements in boilers, more especially that class employed upon vessels, and comprehends certain novel constructions and combinations of parts, resulting in the production of a simple and convenient structure whose center of gravity is low and generating capacity high as compared with other forms of boilers occupying an equivalent space.

20 Referring to the accompanying drawings, wherein my said improvements are illustrated, Figure 1 represents a longitudinal sectional view of the boiler; Fig. 2, a front elevation with a portion of the vertical rear wall broken away. Fig. 3 is a view in elevation of the rear end of the boiler. Fig. 4 is a top plan view of the boiler. Fig. 5 illustrates a modified form of conducting-stud.

Similar letters of reference in the several 30 figures indicate the same parts.

My improved boiler is composed of three "sections," so called—first, the front or horizontal section, A; second, the rear or vertical hollow wall, B, and, third, the series of generating-tubes C.

The front section, A, consists of an arched boiler or jacket comprising the inner and outer plates or water-walls, a a' , heads a^2 a^3 riveted thereto, and interposed plates or flanges along the lower edges, the two heads a^2 a^3 being also provided with corresponding openings for the reception of the door-frame a^4 . At a suitable distance from the front wall or head of the arched boiler, and within the latter, is located 45 the fire wall or bridge a^5 . The bridge a^5 is preferably made hollow, as shown, with a vertical front wall and curved or inclined rear wall, and is provided with a ledge or rest, a^6 , upon which the rear ends of the grate-bars a^7 are supported, the opposite extremities of said bars resting upon a bar, a^8 . The hollow bridge

a^5 is provided with a series of perforations, a^9 , below the grate-bars, for the admission of air, and a second series of openings, a^{10} , at the top, and preferably in rear of the upper edge, 55 through which the heated air is delivered and distributed.

The section B of the boiler consists, essentially, of a hollow wall or column standing vertically in rear of the section A. This hollow wall or column, preferably composed of two water-plates, b b' , and intermediate plates, b^2 , securely united or riveted together, as indicated, is much higher, but of substantially the same width as the section A, so that when 60 the rear edges of the water-plates a a' are riveted to the front plate, b' , the lower portion of the section B will constitute the rear wall of the fire box or chamber. An opening or passage, b^3 , preferably arch-shaped, is formed in 65 the lower end of the section B, through which the products of combustion and flame generated in the combustion-chamber are conducted into the uptake or flue-space.

The third section, C, comprises a series of 70 tubes, c , secured to and extending rearwardly from the wall B and projecting into the uptake or flue-space referred to. The tubes c are threaded into and passed through the front and rear walls or plates of the section B, the 75 rear ends being closed by caps c' and the front ends by caps c^2 , which serve both as packings and jam-nuts. A series of perforations, c^3 , are formed in that portion of the tubes c which, when in place, occupy a position between 80 the walls b b' and within the chamber formed in section B, thus establishing communication 85 between the said chamber and the interior of each tube.

One or more series of tubes c at the top of 90 the section B are connected by branch pipes c^4 with a pipe, c^5 , arranged above the series of tubes c and within the uptake, said pipe c^5 constituting the delivery-pipe and performing, in part at least, the office of a steam-drum. 95

Communication is established between the chambers in sections A and B through openings or passages b^7 and such of the tubes c as project between the plates a a' of the section A, the front ends of said tubes being left open 100 for this purpose.

Upon each side and in rear of the vertical

section B are arranged vertical plates or walls, which, in connection with the section B, form the uptake or passage through which the heated gases and products of combustion are conducted to the chimney or smoke-stack; and it is into said passage or uptake that the tubes *c* project, so that the latter, as well as the vertical wall or section B and supply-pipe *c*, are subjected to the heating action of the gases and products of combustion.

The improved boiler constructed as described constitutes a simple, economical, and efficient steam-generator.

The supply of water in the boiler when in use is maintained at or about the level of the third or fourth series of tubes *c*, counting from the top of section B; hence the chamber in section A is filled, as well as the lower portion of section B and most of the tubes *c* in section C. The weight of water thus distributed, in conjunction with the disposition of the material of the boiler, brings the center of gravity very low, which is particularly desirable when the boiler is designed to be used upon a steam-launch or other vessel. Moreover, by the employment of the vertical section B at the rear end of the horizontal section and the tubes *c*, projecting into the uptake, of which the said section B constitutes one wall, a large generating-surface is provided without unduly increasing the weight or space occupied by the boiler, and at the same time the steam generated in the boiler, and which occupies the interior of the upper series of tubes *c*, is maintained at a high temperature, but a small section of this steam-space—the outer face of section B—being removed from the heating-chambers. The tubes *c*, screwing into both walls or plates of the vertical boiler B, serve the purpose of stay-bolts, and as both ends can be uncovered they can be readily cleaned when desired.

Although, as before mentioned, the boiler described is very efficient, its generating capacity can, as I have discovered, be greatly augmented at relatively slight expense and without involving any material increase in the weight or space occupied. The means whereby this increased generating capacity is attained consists, essentially, of a series of conducting pins or studs *s*, passing through and uniting the water-walls *a a'* of section A, their inner ends being prolonged into the fire-chamber. These pins *s* constitute the stay-bolts for the boiler-section A, and their projecting ends serve as conductors for transmitting heat to the water-walls, as described in my prior application, while the portion of the said bolts *s* which serves to unite the inner and outer water-walls, *a a'*, affords a supplemental generating-surface, maintained at a high heat by conduction from the end projecting into the fire-chamber, which end is raised to a much higher degree of temperature than the inner water-wall, notwithstanding the fact that the said wall, as well as the studs *s*, are subjected to the heating action of the same fire. Instead of em-

ploying solid pins or studs *s* to perform the offices of stay-bolts and supplemental heaters, tubular stay-bolts may be used, as shown in Fig. 5, the inner ends of said tubular stay-bolts being open, while the outer ends are closed by caps *s'*. The stay-bolts *s* are threaded into openings in the water-walls, and are preferably inserted from within the boiler and screwed up tight to their seats at the base of the threaded section, after which the caps *s'* are screwed down tight on the outer projecting ends, forming both a jam-nut and packing. Similar provision is made for increasing the generating capacity of the tubes *c* in the lower portion of section C of the boiler. In this case each tube *c* is provided with a series of conducting-pins, *s''*, projecting radially through the walls of the tubes, as shown, so that the outer ends will serve as conductors and the inner ends as supplemental generators.

In order that the tubes *c* may be the more readily cleaned when the cap is removed from either or both ends, the conducting-pins *s''* are so disposed and arranged as not to occupy the extreme lower portion of the inner walls of the said tubes, leaving a clear space at this point for the passage of the flue cleaning or scraping device.

For the convenience in inserting and removing the tubes *c* when provided with conducting studs or pins *s''*, as described, the said pins are disposed radially on opposite sides of the tubes, leaving the top and bottom surfaces plain, so that each tube can be rotated without coming in contact with the pins on adjacent tubes. This arrangement is especially desirable, in that it permits the tubes *c* to be placed closer together, the one above the other, while allowing a wider space between contiguous rows for the passage of the heated gases and products of combustion.

Having thus described my invention, what I claim as new is—

1. The herein-described improved boiler, consisting of the horizontal fire-box section, the vertical rear section, and the series of tubes attached to and projecting from the said vertical section into the uptake, substantially as and for the purpose set forth.

2. In combination with the horizontal fire-box section, the hollow vertical section B, secured to and forming the rear wall of said fire-box section, and provided at or near its lower end with a passage for the products of combustion, substantially as described.

3. In combination with the fire-box section A, its grate, and bridge-wall, the vertical section B, secured to the rear end of the fire-box section and provided with an opening below the upper edge of the bridge-wall for the passage of the products of combustion, substantially as described.

4. In combination with a horizontal fire-box boiler-section A and vertical boiler-section B, the latter forming the rear wall of the horizontal section and provided with a passage communicating with the uptake, the series of

tubes secured to and projecting rearwardly from the vertical boiler-section and into the uptake, substantially as described.

5. In a boiler such as described, and in combination with the vertical section B, constituting one wall of the uptake, the series of tubes passing through the water-walls of said boiler-section and projecting into the uptake, substantially as described.

10. 6. In a boiler such as described, and in combination with the vertical boiler-section B, constituting one wall of the uptake, the series of tubes passing through and connecting the opposite water-walls of said boiler B and provided with removable caps at one or both ends, substantially as described.

7. In a boiler such as described, and in combination with the vertical section B, forming one wall of the uptake, the series of tubes passing through the water-walls of said boiler-section and projecting into the uptake, and the steam-pipe also located in the uptake and connected to the upper series of tubes, substantially as described.

25. 8. In a boiler such as described, and in combination with the vertical boiler-section B and tube-section C, the horizontal fire-box section A, provided with the grate and hollow bridge-wall, the latter provided with openings for the introduction of air from beneath the grate and its escape into the combustion-chamber, substantially as described.

9. In a boiler such as described, and in combination with the water-walls thereof, a series 35 of hollow stay-bolts whose open inner ends are prolonged beyond the surface of the inner water-wall and projected into the combustion-chamber, substantially as described.

10. In a boiler such as described, and in combination with the water-walls thereof, the tubu-

lar stay-bolts with their inner ends open and projecting into the fire-chamber, said stay-bolts being screwed into the walls of the boiler and their outer ends closed by caps, substantially as described.

11. In a boiler such as described, and in combination with the horizontal fire-box section A, and vertical section B, connected as set forth, the tubes projecting rearwardly from the vertical section into the uptake, each of 50 said tubes being provided with a series of conducting-pins projecting through its walls, substantially as described.

12. In a boiler such as described, and in combination with the vertical section B thereof, 55 the series of tubes with removable caps secured to the walls of said section B, each tube provided with conducting-pins projecting radially on opposite sides, leaving the lower surface of the inner wall of the tube unobstructed, substantially as and for the purpose set forth.

13. In a boiler such as described, and in combination with the section B thereof, a series of tubes, C, provided with conducting-pins on the sides, said tubes being screwed through the 65 water-walls of the boiler-section, substantially as described.

14. In a boiler such as described, and in combination with the vertical section B and inclosing-walls forming the uptake, of the series 70 of tubes C, secured to the said section B and communicating with the interior thereof, said tubes arranged to project within the uptake, being provided with removable caps at opposite ends, substantially as described.
